Attorney

UNITED STATES PATENT OFFICE.

THOMSON MAO, OF SWISSVALE, PENNSYLVANIA.

TABLE ARTICLE.

1,316,314.

Specification of Letters Patent. Patented Sept. 16, 1919.

Application filed January 11, 1919. Serial No. 270,707.

To all whom it may concern:

Be it known that I, THOMSON MAO, a citizen of the Republic of China, residing at Swissvale, in the county of Allegheny and State of Pennsylvania, have invented certain new and useful Improvements in Table Articles, of which the following is a specification, reference being had to the accompanying drawings.

10 This invention relates to certain improvements in table articles, and has relation more particularly to a device of this general character especially designed and adapted for use in the dispensing of milk and sugar, and it is an object of the invention to provide a novel and improved article comprising a containing body divided into two compartments, and wherein the separating partition extends above the containing body to afford a shield to prevent the contents of one compartment accidentally entering the second compartment either upon the filling of a compartment or upon a removal of the contents.

25 A further object of the invention is to provide a novel and improved device of this general character wherein the containing body is divided into two compartments, one of said compartments being forwardly disposed and adapted to contain milk or other liquid, and the second compartment rearwardly disposed and adapted, preferably, to contain sugar, and wherein the partition is arranged and constructed to prevent 30 the contents of the rear compartment passing into the forward compartment during a pouring operation for the contents of the forward compartment and whereby the milk or other liquid when being poured into the 35 front compartment is prevented from splashing or otherwise entering within the rear compartment.

An additional object of the invention is to provide a novel and improved device of 40 this general character including a containing body provided with an outstanding handle for manipulating the body, and wherein said body is intersected by a partition disposed substantially at right angles to the 45 radial plane in which the handle is positioned, so that said containing body is divided into a forward or front compartment and a rear or back compartment, and which compartments are adapted to contain different materials.

The invention consists in the details of

construction and in the combination and arrangement of the several parts of my improved table article whereby certain important advantages are attained and the device 60 rendered simpler, less expensive and otherwise more convenient and advantageous for use, as will be hereinafter more fully set forth.

The novel features of my invention will 65 hereinafter be definitely claimed.

In order that my invention may be the better understood, I will now proceed to describe the same with reference to the accompanying drawings, wherein:

70 Figure 1 is a view in top plan of a table article constructed in accordance with an embodiment of my invention;

75 Fig. 2 is a view in front elevation of the device as herein disclosed; and

Fig. 3 is a sectional view taken axially through the device as herein embodied.

As disclosed in the accompanying drawings, B denotes a containing body of any desired configuration and dimensions, and 80 which has its upper end open and its closed end provided with a supporting base 1 so that the device may be readily positioned upon a table or other supporting surface. The open end portion of the body B is provided 85 with a discharge spout 2, and which portion of the body B is termed the front of the body. Extending outwardly from the rear portion of the body and preferably in the same vertical or radial plane as the spout 90 2 is a handle or hand grasp 3.

Rearwardly of its axial center the body B is intersected by a transversely disposed partition 4 herein disclosed as integrally formed with the body B and said partition 4 divides 95 the containing body B into the front compartment F and the rear compartment R.

The partition 4 is substantially concavo-convex with its concave face forwardly directed or disposed in a direction toward the 100 compartment F or the spout 2 and the upper end portion 5 of the partition extends above the upper or open end of the body B and said extended portion 5, as herein embodied, partially overlies the upper end of the compartment R as is particularly illustrated in Fig. 3 of the accompanying drawings.

In the present embodiment of my invention, the compartment R is of less capacity than the compartment F, and said compartment R is primarily adapted to contain a supply of sugar and an amount equal to the

quantity necessary for one day's use, and is of a depth sufficient to permit the requisite insertion of a spoon therein so that the contents of said compartment R may be readily removed when the occasions of practice require.

By having the partition 4 substantially concavo-convex with the concave face thereof forwardly directed, it will be at once self evident that the convex face of said partition, together with the convex face of the extension 5 thereof, serves to prevent the sugar as it is being removed from the compartment R being accidentally thrown or forced into the compartment F.

The forward or front compartment F is adapted to contain liquid, preferably milk, and it will be at once self evident that the extension 5 of the partition 4 readily permits the contents of the compartment F to be poured therefrom through the spout 2 with the substantial elimination of the possibility of the contents of the compartment R passing into the compartment F. It is also to be stated that the particular formation or curvature of the partition 4 and the extension 5 thereof serves as a shield or guard to prevent the milk or other liquid as it is poured into the compartment F from spattering or otherwise accidentally entering the compartment R.

From the foregoing description, it is thought to be obvious that a table article constructed in accordance with my inven-

tion is particularly well adapted for use by reason of the convenience and facility with which it may be assembled and operated and it will also be obvious that my invention is susceptible of some change and modification without departing from the principles and spirit thereof, and for this reason I do not wish to be understood as limiting myself to the precise arrangement and formation of the several parts herein shown in carrying out my invention in practice except as hereinafter claimed.

I claim:

An article of the class described comprising a dispensing body having one end open, said open end portion being provided with a discharge spout, and a partition intersecting the body at substantially right angles to the radial plane in which the spout is arranged and dividing the body into two compartments, said partition being substantially concavo-convex in form with its concave face disposed in a direction away from the spout, said partition extending beyond the open end of the body with the upper portion partially overlying the compartment at the side of the partition remote from the spout.

In testimony whereof I hereunto affix my signature in the presence of two witnesses.

THOMSON MAO.

Witnesses:

I. HSIANG PEI,
C. BERTONEINI.
